UNITED STATES PATENT OFFICE.

AUGUST C. BECKER, OF ELMINS, WEST VIRGINIA, ASSIGNOR OF ONE-HALF TO O. A. KNAPP, OF ELMINS, WEST VIRGINIA.

BOOT OR SHOE.

1,154,360.

Specification of Letters Patent. Patented Sept. 21, 1915.

Application filed December 12, 1914. Serial No. 876,915.

To all whom it may concern:

Be it known that I, AUGUST C. BECKER, a citizen of the United States, residing at Elkins, West Virginia, have invented certain new and useful Improvements in Boots or Shoes, of which the following is a specification.

This invention relates to improvements in boots or shoes.

10 The main objects of this invention are: First, to provide an improved welt boot or shoe. Second, to provide an improved boot or shoe having a combined insole and welt formed in one piece of uniform thickness 15 and without cutting or channeling. Third, to provide an improved welt boot or shoe which is economical to produce both in the matter of material and labor and one in which the upper is very securely attached to 20 the sole.

Further objects, and objects relating to structural details, will definitely appear from the detailed description to follow.

I accomplish the objects of my invention 25 by the devices and means described in the following specification.

The invention is clearly defined and pointed out in the claims.

A structure which is a preferred embodiment of my invention is clearly illustrated in the accompanying drawing forming a part 30 of this specification, in which:

Figure I is a perspective view of a shoe embodying the features of my invention. 35 Fig. II is a bottom view of the insole showing one of the steps of attaching the upper thereto. Fig. III is a bottom view of the combined insole and welt after the upper has been completely attached thereto. Fig. IV

40 is an enlarged detail section on a line corresponding to line 4—4 of Fig. II, showing the first step of attaching the upper and insole. Fig. V is an enlarged detail section on a line corresponding to line 5—5 of Fig. III, showing

45 the upper completely attached to the insole. Fig. VI is a transverse section through my improved boot or shoe on a line corresponding to line 6—6 of Fig. I. Fig. VII is a detail section, corresponding to that 50 of Fig. V, of a slightly modified embodiment of my invention.

In the drawing similar reference characters refer to similar parts throughout the several views, and the sectional views are

taken looking in the direction of the little 55 arrows at the ends of the section lines.

Referring to the drawing, the upper 1, in the structure illustrated, is provided with a lining 2. The upper is attached to the combined insole and welt 3 by lapping its edges 60 upon the insole, as shown in Fig. IV, and securing thereto by the through and through stitches 4. The edges of the upper are preferably arranged outwardly as shown. After the upper is secured to the insole by the 65 stitches 4 the insole is folded to provide the continuous fold 5 embracing the edges of the upper, as shown in Figs. V and VI. The insole and upper are further secured together by the through and through stitches 70 6 which pass through both walls or sides of the fold and the edges of the upper clamping the fold firmly upon the edges of the upper and very securely attaching the parts.

The portion of the insole on the outside of 75 this fold 5 constitutes the welt 7. The outer sole 8 is secured to the welt by the stitches 9, as is usual practice. A filler 10 is arranged in the recess of the insole formed by the fold. A finishing inner sole 11 may be 80 provided if desired. By this arrangement of parts the insole and upper are connected in a very secure manner and at the same time so that the upper is not likely to tear loose along the line of stitching. The sole is 85 comparatively flexible and the welt cannot become loosened as sometimes occurs where separate welt pieces are employed. A further advantage is that a very effective watertight seam is provided between the upper 90 and the insole.

In Fig. VII I show a modification of my improvements in which modification the upper is infolded in the fold 5 and secured entirely by the stitches 6 through the fold, the 95 preliminary stitching 4 to the insole being omitted.

I have not illustrated or described certain modifications or embodiments of my invention which I contemplate as being desirable 100 under certain conditions as I believe the disclosure made will enable those skilled in the art to which my invention relates to embody or adapt the same as conditions may require. I desire, however, to be understood as claiming my improvements specifically in the form illustrated as well as broadly within the scope of the appended claims. 105

Having thus described my invention, what I claim as new and desire to secure by Letters Patent, is:

1. In a structure of the class described, 5 the combination of an upper, a combined insole and welt of uniform thickness, said insole being provided with a continuous fold embracing the edges of said upper, said upper being secured in said fold by a row of 10 stitches through one wall of the fold and the edge of the upper and by a row of stitches through both walls of the fold and the edges of the upper, the portion of the insole on the outside of said fold constituting the 15 welt, a filler arranged within the recess of the insole formed by said fold, and an outer sole attached to the welt portion of said insole.
2. In a boot or shoe, the combination of 20 an upper, a combined insole and welt, said insole being provided with a continuous fold embracing the edges of said upper, said upper being secured in said fold by a row of 25 stitches through one wall of the fold and the edge of the upper and by a row of stitches through both walls of the fold and the edges of the upper, the portion of the insole on the outside of said fold constituting the welt, a 30 filler arranged within the recess of the insole formed by said fold, and an outer sole attached to the welt portion of said insole.
3. In a boot or shoe, the combination of 35 an upper, a combined insole and welt of uniform thickness, provided with a fold embracing the edges of said upper, said upper being secured in said fold by stitches through both walls of the fold and the edges of the upper, the portion of the insole on the outside of said fold constituting the welt, a

filler arranged within the recess of the insole formed by said fold, and an outer sole attached to the welt portion of said insole.

4. A boot or shoe comprising an upper and a combined insole and welt of uniform thickness, the edges of said upper being embraced in a continuous fold in said insole and secured therein by a row of stitches through one wall of the fold and the edge of the upper and by a row of stitches through both walls of the fold and the edges of the upper, the portion of the insole on the outside of said fold constituting the welt.

5. A boot or shoe comprising an upper and a combined insole and welt, the edges of said upper being embraced in a fold in said insole and secured by a row of stitches through one wall of the fold and the edge of the upper and by a row of stitches through the fold and the edge of the upper, the portion of the insole on the outside of said fold constituting a welt.

6. A boot or shoe comprising an upper and a combined insole and welt, said combined insole and welt being of uniform thickness and provided with a fold embracing the edges of said upper, said upper being secured in said fold by stitches through both walls of the fold and the edges of the upper, the portion of the insole on the outside of said fold constituting the welt.

In witness whereof, I have hereunto set my hand and seal in the presence of two witnesses.

AUGUST C. BECKER. [L.S.]
